APPARATUS FOR FORMING CAN BODIES

Frank L. Darling, Teaneck, N. J., assignor, by
mesne assignments, to Crown Can Company,
Philadelphia, Pa., a corporation of Pennsyl-
vania

Application December 16, 1936, Serial No. 116,211
21 Claims. (Cl. 153—32)

The principal object of the present invention is to provide a method and apparatus for forming containers to true body contour, particularly containers of other than cylindrical shape, such as can bodies of oval contour.

The invention is adapted to form a can body to true contour after the circumferential dimension of the body has been determined by engaging and locking the edges of the body blank into a side seam, and before the ends of the can have been attached thereto.

Another object of the invention is to provide a method and apparatus for forming a can into true body contour, by expanding the body outwardly against the walls of a can body mold, without the necessity of providing a fluid-tight mold.

Another object of the invention is to provide a can body forming machine which will operate successively upon a series of formed can body blanks fed thereto.

While the present invention may be used most advantageously in connection with the forming of can bodies of other than cylindrical shape, it will be obvious that the invention may be practiced with success in forming cylindrical cans to true body contour.

The drawings disclose an apparatus for forming a can body of oval or elliptical contour, cans of this type being generally used for talcum powder, dental powder and the like. In the drawings, which are illustrative and in no sense restrictive:

Figure 1 is a central vertical sectional view of the can body forming machine of the present invention.

Figure 2 is an enlarged horizontal cross sectional view of the can body mold sections, taken along the line 2—2 of Figure 1.

Figure 3 is a rear elevational view of a portion of the machine of the present invention.

Figure 4 is a front elevational view of the machine, showing the plurality of can body molds mounted upon the revolving disc.

Figure 5 is a side elevational view of a can body blank before being operated upon by the machine of the present invention, and

Figure 6 is a horizontal sectional view of the can body blank taken along the line 6—6 of Figure 5.

According to present practice, can bodies are formed upon a horn by wrapping the blank about the horn with pivoted wings, or in the case of cylindrical cans, by rolling the blank on to the horn with forming rollers. In either case, but particularly when the bodies are formed about

the horn with pivoted wings, the formed body is not of true contour, but is characterized by flat areas or panels which distort the surface. This is especially true in the case of can bodies of other than cylindrical shape, such as oval bodies, as shown in Figures 5 and 6. Bodies of this type are difficult to form to true contour, as their curvature is not uniform, but is continuously changing at every point around the body. Referring to Figure 6, it will be noted that in horizontal cross section, the can body which has been formed and side seamed on a horn, is made up of a plurality of substantially tangential areas or panels, rather than being of true curvature at every point.

In the practice of the present invention, a can body blank which has been formed and side seamed on a horn, is expanded against the walls of a mold of true body contour by a confined body of fluid under pressure disposed within the can body when the latter is in the mold. An end is then seamed to the can, after which the can is filled and a top is seamed thereto, providing a finished package.

The appearance of the can is greatly enhanced by the expanding operation, as the outer wall thereof receives paint of a color and design to designate the product, and any flat areas result in shadows which detract from the beauty of the package.

The machine disclosed herein is adapted to receive formed can body blanks of oval contour which have previously had their side edges engaged and locked in a side seam to fix the circumferential dimension of the can body. While the molds of the machine disclosed are oval in shape, to form oval can bodies, it is obvious that molds of different contour may be provided to form other types of can bodies.

In Figure 1, the frame of the machine is shown at 10, said frame including a suitable base fixed to the floor. The frame comprises an upstanding pedestal having a horizontal bore 12 therethrough, providing a bearing for a horizontal rotatable hollow shaft 14, which carries the can body mold support or disc hereinafter described. Disposed within the hollow rotatable shaft 14 is a hollow fixed shaft 16, which constitutes a part of the frame, said shaft being maintained in fixed position by a bracket 18 which encompasses the rearward end of said shaft and is keyed thereto as shown at 20.

The inner end of the rotatable shaft 14 is integral with the can body mold support 22 which is shown in the form of a rotatable disc.

5 Adjacent the perimeter of the support or disc 22, a plurality of can body mold supporting brackets 24 are secured as by means of bolts 26. As shown in Figure 2, each can body mold comprises a pair of sections 28 and 30 which are pivoted on a pin 32, which is threaded into the periphery of the disc 22, as shown in Figure 1. Each of the mold sections 28 and 30 have operating arms 34 and 36 respectively which extend 10 rearwardly beyond the pivot 32, and the rearward ends of these arms are normally forced toward one another to keep the mold in open condition by a spring 38 which extends between the rearward ends of said arms.

15 The mold sections are moved toward each other along the outer faces of the brackets 24 to close the molds about the can bodies by closing members in the form of rods 39, mounted for radial movement in brackets 40 carried on the rearward 20 face of the disc 22. At their outer ends, the rods carry pointed cam members 41 which are adapted to move between the arms 34 and 36 when the rods are moved outwardly to close the mold sections against the action of the springs 38. The 25 inner ends of the rods carry rollers 42 which move upon a cam track 43 extending around the frame, and the rods are normally pressed inwardly by springs 44.

Referring to Figure 4, the can bodies are received into the molds at station R when the supporting disc is moving in a clockwise direction, and any suitable feeding means 45 is provided at said station for dropping the cans into the open molds. At station R, the roller 42 of a particular closing member is in engagement with the 30 lower portion 46 of the cam track 43, so that the spring 38 of the particular mold retains the mold sections in open condition for the reception of a can body. Adjacent the upper portion of the machine, the cam track 42 rises to a high portion 48, which forces the particular rod 39 outwardly between the arms 34 and 36 to close the mold sections about the can body which has been received at the station R. The can body is then carried 35 through substantially 180° with the mold in closed condition until just prior to the time when it reaches the discharging station D, at which time the high portion 48 of the cam track 43 ends, and the lower portion 46 is resumed, so that the rod 39 is retracted and the springs 39 again 40 open the mold sections to discharge the can body which has been expanded between the receiving and discharging stations in a manner hereinafter described.

50 Referring to Figure 1, the forward end of the fixed hollow shaft 16 terminates in a flat valve plate 50 having an arcuate fluid inlet opening 52 in its rearward wall and a fluid vent opening 54 extending entirely through the plate. The inner 55 face of the fixed plate 50 has formed thereon an arcuate channel 55 in communication with the vent opening 54 and forming a part of the vent passage. The relative positions of said openings are disclosed in Figure 4, opening 52 being positioned at the upper side of the plate, while the opening 54 is at the lower side of the plate. The opening 52 is in communication with the interior 60 passage 56 of the fixed shaft 16 by a radial passage 58 in the interior of said plate. The plate 65 50 with its openings and passages provides a valve member fixed to the frame for cooperation with a movable valve member carried by the can supporting disc, as described below.

70 Disposed centrally of and on the forward face 75 of the disc 22 is a circular valve plate 60, provided

with a plurality of ports 62, there being one port for each mold mounted on the disc. Ports 62 communicate with radial passages 64 in the plate into which passages are connected pipes 66 which carry the expanding fluid to the can body molds. Each pipe 66 terminates in a nipple 68 which passes through its respective can body mold bracket, each nipple having a head 70 disposed within a rubber expanding mandrel 72. The mandrels may be of any shape to conform with the desired form of can body and the interior of mold parts 28 and 30, and in the present instance, the mandrels are of oval contour. The nipples 68 are provided with threaded extensions inside the brackets 24 and onto which are threaded nuts 74, 15 which compress portions of the mandrels through which the nipples extend forming a seal where the pipes 66 enter the mandrels.

10 The machine is driven either continuously or intermittently from a motor 76, which drives a 20 shaft 78, which shaft in turn rotates a pulley 80 through suitable reduction gear 82. A belt 84 connects pulley 80 with another pulley 86 which is keyed to the rotatable shaft 14, and thus the can supporting disc is rotated through said belt 25 and said shaft.

The fixed shaft 16 has keyed thereto a collar 90 which bears against the rearward face of the pulley 86, and the engaging faces of the collar and pulley are provided with aligned annular grooves 30 carrying ball bearings 92. The fixed shaft 16 also carries an additional collar 94 spaced rearwardly of the collar 90, and between said collars is a relatively heavy spring 96 which biases the fixed shaft 16 rearwardly of the machine, 35 thus holding the rearward face of the fixed valve plate 50 in tight engagement with the rotatable plate 60 carried by the disc 22.

The operation of the machine will be apparent from the above description and is briefly as follows. The open ended container bodies are fed 40 into the molds as the same successively pass the station R (Fig. 4) in any appropriate manner, and when a particular mold is at station R, it is in open condition by reason of the fact that its roller 42 is on the lower portion 46 of the cam track 43, the spring 38 retaining said mold in open condition. The can body is fed into the mold in proper position so that it will surround the deflated mandrel 72 as shown in Figure 4, with the inner 50 end of the body resting on the outer face of the bracket 24. As the disc 22 rotates the particular mold beyond the station R, the high portion 48 of the cam 43 moves the rod 39 outwardly, thus closing the mold sections around the can body 55 and mandrel, the mold sections pivoting on the pin 32. After the mold sections are closed, the particular opening 62 in the rotatable plate comes into alignment with the opening 52 in the fixed plate 50, as shown in Figure 4, and air or other 60 fluid under pressure flows from any appropriate source connected with passage 56 through passage 58 and pipe 66 to the interior of the mandrel, expanding the same and likewise expanding the walls of the can body against the inner contour 65 of the mold, thus removing all of the panels or flat areas in the body of the can.

Further rotation of the disc 22 brings the mold containing the can body which has been expanded to position where the opening 62 corresponding 70 with this mold section registers with the vent passage 55 in the fixed plate 50. At this time, the fluid will be vented from the interior of the mandrel, permitting the same to contract. The particular roller 42 passes to the lower portion 46 of the cam 75

track 43 shortly before or simultaneously with the arrival of the particular mold at the discharge station D, and the spring 38 then separates the mold sections, thus permitting the can body which has been formed to true contour to drop onto a conveyor 100 which carries the body away from the machine.

It will be observed that by reason of the provision of the fluid-tight mandrel 72, it will be unnecessary to provide mold sections which are fluid-tight when they are moved to closed condition, and during the expanding of the can body. The use of such a mandrel also protects the interior of the can from the expanding gas used, so that steam or other like gases may be used as the expanding medium. The interior of the body is shielded from any moisture present in the expanding medium, so that the can may be filled immediately after leaving the machine without danger of injuring the contents. The body of fluid being confined in the mandrel during the expanding operation, the cams 41 provide a sufficient locking means to keep the molds in closed condition during said operation. However, if desired, any suitable locking means may be provided to lock the mold sections together during the expanding operation, and this locking means may be automatically operated in any desired manner in coordination with the rotation of the disc 22.

Any acceptable means may be provided for feeding the can bodies to the machine at the station R, and any suitable conveying mechanism may be provided at station D to carry the form bodies away from the machine. The disc 22 may be rotated either continuously or intermittently, depending on the type of feeding mechanism utilized.

After the can bodies are carried away on the conveyor 100, bottom ends are seamed therein, after which the bodies are filled and the top ends applied in the well known manner.

Various modifications of the apparatus and method disclosed herein may be made without departing from the scope of the invention.

I claim:

1. In apparatus of the character described, a movable support, a can body mold mounted on said support, said mold being adapted to receive a can body therein, and means coordinated with the movement of said support for flowing fluid under pressure into the can body when the latter is positioned in said mold to expand the can body against the wall of said mold.

2. In apparatus of the character described, a movable support, a can body mold mounted on said support, said mold being adapted to receive a can body therein, and means coordinated with the movement of said support for flowing fluid under pressure into the can body when the latter is positioned in said mold to expand the can body against the wall of said mold, and for venting the fluid from the can body after the expansion operation has been performed.

3. In apparatus of the character described, a movable support, a can body mold mounted on said support, means for moving said support from a station where a can body is received into said mold to a station where the can body is discharged therefrom, and means coordinated with the movement of said support for flowing fluid under pressure into the can body to expand the same against the wall of said mold after said mold has received the can body at the receiving station.

4. In apparatus of the character described, a movable support, a can body mold mounted on said support, means for moving said support from a station where a can body is received into said mold to a station where the can body is discharged therefrom, and means coordinated with the movement of said support for flowing fluid under pressure into the can body to expand the same against the wall of said mold after said mold has received the can body at the receiving station, and for venting the fluid from the can body before said mold has discharged the can body at the discharging station.

5. In apparatus of the character described, a movable support, a sectional can body mold mounted on said support, means for moving said support from a station where a can body is received into said mold to a station where the can body is discharged therefrom, means for opening said mold to receive a can body at the receiving station and to discharge a can body at the discharging station, means for closing said mold about the can body between the stations, and means coordinated with said mold opening and closing means for flowing fluid under pressure into the can body to expand the same against the wall of said mold while said mold is in closed condition.

6. In apparatus of the character described, a movable support, a sectional can body mold mounted on said support, means for moving said support from a station where a can body is received into said mold to a station where the can body is discharged therefrom, means for opening said mold to receive a can body at the receiving station and to discharge a can body at the discharging station, means for closing said mold about the can body between the stations, means coordinated with said mold opening and closing means for flowing fluid under pressure into the can body to expand the same against the wall of said mold while said mold is in closed condition, and means for venting the fluid from the can body before said mold has discharged the can body at the discharging station.

7. In apparatus of the character described, a movable support, a can body mold mounted on said support, an inflatable mandrel in said mold, means for moving said support from a station where a can body is received into said mold surrounding said mandrel, to a station where the can body is discharged therefrom, and means coordinated with the movement of said support for flowing fluid under pressure into said mandrel to expand the can body against the wall of said mold, after said mold has received the can body at the receiving station.

8. In apparatus of the character described, a movable support, a can body mold mounted on said support, an inflatable mandrel in said mold, means for moving said support from a station where a can body is received into said mold surrounding said mandrel to a station where said can body is discharged therefrom, and means coordinated with the movement of said support for flowing fluid under pressure into said mandrel to expand the can body against the wall of said mold after said mold has received the can body at the receiving station, and means for venting the fluid from said mandrel before the can body is discharged from said mold at the discharging station.

9. In apparatus of the character described, a movable support, a sectional can body mold mounted on said support, an inflatable mandrel in said mold, means for moving said support from

- 5 a station where a can body is received into said mold surrounding said mandrel to a station where the can body is discharged therefrom, means for opening said mold to receive a can body at the receiving station and to discharge a can body at the discharging station, means for closing said mold about the can body between said stations, and means coordinated with said mold opening and closing means for flowing fluid under pressure into said mandrel to expand the can body 10 against the wall of said mold while said mold is in closed condition, and means for venting the fluid from said mandrel before the can body is discharged from said mold at the discharging station.
- 15 10. In apparatus of the character described, a source of fluid under pressure, a movable support, a can body mold mounted on said support, means for moving said support from a station where a can body is received into said mold to a station where the can body is discharged therefrom, and valve means on said support coordinated with the movement thereof for flowing fluid under pressure from said source into the can body to expand the same against the wall of said mold after said mold has received the can body at the receiving station.
- 20 11. In apparatus of the character described, a source of fluid under pressure, a stationary frame, a support mounted for movement on said frame, a can body mold mounted on said support, means for moving said support from a station where a can body is received into said mold to a station where the can body is discharged therefrom, and cooperating means on said frame and said support coordinated with the movement of the latter for flowing fluid under pressure from said source into the can body to expand the same against the wall of said mold after said mold has received the can body at the receiving station.
- 25 12. In apparatus of the character described, a source of fluid under pressure, a stationary frame, a support mounted for movement on said frame, a can body mold mounted on said support, means for moving said support from a station where a can body is received into said mold to a station where the can body is discharged therefrom, and cooperating valve means on said frame and said support coordinated with the movement of the latter for flowing fluid under pressure from said source into the can body to expand the same against the wall of said mold after said mold has received the can body at the receiving station.
- 30 13. In apparatus of the character described, a rotatable disc, a plurality of can body molds mounted on said disc, means for rotating said disc to move said molds successively past a station where can bodies are received in said molds, and past a station where the can bodies are discharged therefrom, and means coordinated with the rotation of said disc for successively flowing fluid under pressure into the can bodies to expand the same against the walls of said molds after said molds have received the can bodies at the receiving station.
- 35 14. In apparatus of the character described, a frame, a disc mounted on said frame for rotation about a horizontal axis, a plurality of sectional can body molds mounted on said disc adjacent the periphery thereof, means for rotating said disc to move said molds successively past a station at the upper end of said frame where can bodies are dropped into said molds, and past a station at the lower end of said frame where the can bodies are dropped from said molds.
- 40 means for opening said molds to receive can bodies at the receiving station and to discharge the can bodies at the discharging station, means for closing said molds about the can bodies between the stations, and means coordinated with said mold opening and closing means for successively flowing fluid under pressure into the can bodies to expand the same against the walls of said molds while the latter are in closed condition.
- 45 15. In apparatus of the character described, a movable support, a can body mold mounted on said support, an inflatable mandrel within said mold, said mold being adapted to receive a can body therein surrounding said mandrel, and means coordinated with the movement of said support for flowing fluid under pressure into said mandrel to expand the can body against the wall of said mold.
- 50 16. In apparatus of the character described, a movable support, a can body mold mounted on said support, an inflatable mandrel within said mold, said mold being adapted to receive a can body therein surrounding said mandrel, and means coordinated with the movement of said support for flowing fluid under pressure into said mandrel to expand the can body against the wall of said mold, and for venting the fluid from said mandrel after the expansion operation has been performed.
- 55 17. In apparatus of the character described, a movable support, a plurality of sectional can body molds mounted on said support, means for moving said support to move said molds successively past a station where can bodies are received into said molds, and past a station where the can bodies are discharged therefrom, means for successively opening said molds to receive can bodies at the receiving station and to discharge said bodies at the discharging station, means for successively closing said molds about the can bodies between said stations, and means coordinated with the movement of said support and said mold opening and closing means for successively flowing fluid under pressure into the can bodies to expand the same against the walls of said molds while the latter are in closed condition.
- 60 18. In apparatus of the character described, a movable support, a plurality of sectional can body molds mounted on said support, an inflatable mandrel in each of said molds, means for moving said support from a station where can bodies are successively received in said molds surrounding said mandrels to a station where the can bodies are discharged therefrom, means for successively opening said molds to receive can bodies at the receiving station and to discharge can bodies at the discharging station, means for successively closing said molds about the can bodies between said stations, means coordinated with the movement of said support and said mold opening and closing means for successively flowing fluid under pressure into said mandrel to expand the can bodies against the walls of said molds while said molds are in closed condition, and means for venting the fluid from said mandrels before the can bodies are discharged from said molds at the discharging station.
- 65 19. In an apparatus of the character described, a source of fluid under pressure, a stationary frame, a support mounted for movement on said frame, a can body mold mounted on said support, means for moving said support from a station where a can body is received into said mold to a station where a can body is discharged therefrom, a valve plate on said frame, a cooperating valve plate on said support, said valve plates hav-

- ing engaging faces, the face of the valve plate on said support moving with respect to the face of the valve plate on said frame, said frame plate having a fluid inlet opening in the face thereof which communicates with said source of fluid under pressure, said support plate having a port in the face thereof communicating with the interior of the can body in said mold, said port and inlet opening being adapted to register during the movement of said support after said mold has received the can body at the receiving station, whereby fluid under pressure flows from said source into the can body to expand the same against the wall of said mold.
15. 20. In an apparatus of the character described, a source of fluid under pressure, a stationary frame, a rotatable support, a plurality of can body molds mounted on said support, means for rotating said support to move said molds successively past a station where can bodies are received in said molds, and past a station where the can bodies are discharged therefrom, the face of the valve plate on said support moving with respect to the face of the valve plate on said frame, said frame plate having a fluid inlet opening in the face thereof which communicates with said source of fluid under pressure, and a vent opening spaced from said inlet opening, said support plate having a plurality of ports in the face thereof, each of which communicates respectively with the interior of a can body in its mold, each of said ports being adapted to successively register with said inlet opening during the movement of said support after its respective mold has received a can body at the receiving
- station, whereby fluid under pressure flows from said source into the can bodies to expand the same against the walls of said molds, each of said parts being adapted to thereafter successively register with said vent opening to relieve the pressure from said can bodies.
21. In an apparatus of the character described, a source of fluid under pressure, a stationary frame, a rotatable support, a plurality of sectional can body molds mounted on said support, means for rotating said support to move said molds successively past a station where can bodies are received into said mold, and past a station where the can bodies are discharged therefrom, means for successively opening said molds to receive can bodies at the receiving station and to discharge said bodies at the discharging station, means for successively closing said molds about the can bodies between said stations, a valve plate on said frame, a cooperating valve plate on said support, said valve plates having engaging faces, the face of the valve plate on said support moving with respect to the face of the valve plate on said frame, said frame plate having a fluid inlet opening in the face thereof which communicates with said source of fluid under pressure, said support plate having a plurality of ports in the face thereof, each of which communicates respectively with the interior of a can body in its mold, each of said ports being adapted to successively register with said inlet opening during the movement of said support when its mold is in closed condition, whereby fluid under pressure flows from said source into the can bodies to expand the same against the walls of said molds.

FRANK L. DARLING.
